UNITED STATES PATENT OFFICE

2,537,821

HAIR DRIER

Antal Fodor, deceased, late of New York, N. Y., by
 Jeanne Blanche Fodor, administratrix, New
 York, N. Y., assignor to American Thermo-Tech
 Corporation, New York, N. Y.

Application August 23, 1949, Serial No. 111,886

4 Claims. (Cl. 219—38)

1

This invention relates to space heaters in general, similar to that disclosed in pending application Serial No. 26,777, filed May 13, 1948, matured into Patent No. 2,501,812, issued March 28, 1950, but particularly deals with directional heaters such as hair dryers.

The principal object of the present invention is the provision of a rather inexpensive, simple, safe and easily operable device of that kind, which, without the use of mechanical means, such as fans or blowers, will produce a rapid flow of heated air in any desired direction.

Another object of this invention is to provide a hair drier comprising an electrically heated appliance, wherein air heated by radiation is converted into a high velocity current of heated air, and wherein means are provided for concentrating and directing such current of heated air wherever desired.

The foregoing and still further important objects and additional advantages of the present invention will become more fully apparent from the ensuing description, in conjunction with the accompanying drawings wherein:

Fig. 1 is a perspective view of a hair drier constructed in accordance with the present invention;

Fig. 2 is a vertical section taken approximately along line 2—2 of Fig. 1; and

Fig. 3 is a front elevation of the hair drier proper, partly in section.

In Fig. 1 there is illustrated a hollow base 10, containing a coiled electric cord 11, which latter is preferably automatically wound up by spring means, not shown, similar in principle to the winding up of a flexible measuring tape. Extending from base 10 is a tubular member 12 in which is telescopingly and adjustably mounted another tubular member 13, the latter being held at any desired height by a thumb screw 14. Member 13 supports by means of disk 13' the electric hair drier generally indicated at 15. The hair drier comprises an electric heating element 16 which is enclosed in a Venturi structure 17, composed of a closed bottom 18 from which extends upwardly the lower Venturi member 19 terminating in a throat portion 20 and from which throat portion extends upwardly the upper Venturi member 21 terminating in an outlet 22. The top portion of member 21 is preferably curved for smoothly guiding air outwardly. The sides of the lower Venturi member 19 are provided near bottom 18 with relatively large air intake openings 23.

Venturi structure 17 is completely enclosed within and is spaced from the walls of a hull 24, the latter being provided, near outlet 22 of

2

the Venturi structure, with outlet openings 25 and 26, whereas at the bottom of the hull are arranged air inlet openings 27. The upper member of hull 24 is curved similarly to the curved top portion of Venturi member 21 and for the same purpose. The Venturi structure is virtually suspended within hull 24. The entire hull 24 is again completely enclosed in and is spaced from the walls of an outer cover 28, which is preferably made of insulating material or a combination of a metal structure interiorly lined with insulating matter. Outer cover 28 comprises a substantially closed, box-like design, the bottom 29 of which is provided with a plurality of perforations 30 serving as air inlets. The top wall 31 of the cover is inclined or curved in substantially the same manner as is the upper member of hull 24 and the top portion of upper Venturi member 21. At the upper end of the front wall of cover 28 there is provided a single air outlet aperture 32. The inclined upper wall ends of the cover of the hull and of the Venturi structure are all directed toward air outlet 32 of the cover.

Hingedly secured with or otherwise rendered adjustable and movable in respect to top wall 31 of outer cover 28 is an extension 33 provided with hinged side shields 34, whereby heated air escaping through openings 32 may be concentrated against an object and may be guided in any desired direction. Extension 33 may be not only tilted about hinge 35 but also adjusted bodily by means of slots 36 and thumb screw 37 in respect to outer cover 28.

Between the bottom of the outer cover and bottom 18 of Venturi structure 17 there is preferably provided an insulating member 38 supported by a spacer 39 and serving as a heat shield for heating element 16.

Operating principle

When heating element 16 is energized, air entering through the perforations 36 in bottom 29 of cover 28 and passing through openings 23 into Venturi structure 17 becomes heated. The thus heated air is forced through throat 20, whereby its velocity is materially increased. Both element 16 as well as the hot air heat the walls of Venturi structure 17, which walls in turn heat the walls of hull 24 by radiation.

While the air heated directly by element 16 escapes through outlet 22, fresh air is caused to enter through openings 23. In addition to the air directly heated by element 16 in the Venturi structure, the air between the walls of that structure and the walls of hull 24 becomes heated also,

but to a lesser degree, and escapes through openings 25 and 26 of the hull, adjacent to opening 22 of Venturi structure 17. Still additional air is heated by the outer surfaces of the heated hull walls and passes upwardly between the hull and the insulated walls of the outer cover. All of the combined heated air currents escape through the single top opening 32 provided in the outer cover, from where they are directed by extension 33 to the best advantage.

Inasmuch as the outer cover structure is either wholly made from or is lined with insulating material, the device is perfectly safe to direct touch, so that accidental burning is prevented.

The air escaping through opening 32 is of a sufficient velocity that it may be effectively directed by extension 33 and shields 34 to any desired point or area.

From the above description it becomes clearly evident that the air heated both by direct contact with element 16 and by radiation within the Venturi structure and hull 24 is first, so-to-speak, trapped or accumulated within outer cover 23, whereupon it issues in the form of an air current from opening 32 of the cover at a rather high velocity and at a relatively high temperature. This hot air current has proven to be most effective for rapidly drying hair or to serve as a drying appliance for other uses, without the employment of mechanical means for producing a forced air movement.

The entire hair drier is, as stated before, supported by an adjustable stanchion so that it can be raised or lowered at will. As also stated, the device is perfectly safe to touch and safe in use and most inexpensive in its structural arrangement and its maintenance.

While only a specific form of the device is illustrated in the drawing and described in the specification, it is quite evident that changes and improvements, necessitated by specific requirements for different uses of the device, may be readily incorporated, without departing from the broad scope of this invention, as defined in the annexed claims.

What is claimed as new is:

1. A heating device of the class indicated, comprising a substantially closed outer, insulated casing or cover provided with bottom air intakes and a single air outlet at the upper end of one of its sides, a hull within the cover, a Venturi structure within the hull, bottom air intakes and top air outlets provided in both the hull and the Venturi structure, said top air outlets of the hull and of the Venturi structure being directed toward the single air outlet of the outer casing, an electric heating element within the Venturi structure, adjustable means secured to the top end of the cover for directing hot air issuing from the air outlet of the cover, and an adjustable support for the cover.

2. In a heating device of the class indicated, a substantially closed cover having a perforated bottom and a single air outlet at the upper end of the front wall of the cover, a hull within the cover but spaced from its walls, a Venturi structure suspended within and spaced from the walls of the hull, a heating element within the Venturi structure, the upper wall portions of the Venturi structure, of the hull and of the cover being inclined and directed toward the air outlet of the

cover; said Venturi structure and said hull having air intakes at their bottom and air outlets at their upper ends, said air outlets being directed toward the single air outlet of the cover; an adjustable extension in mobile association with the upper wall portion of the cover and being provided with adjustable side shields for concentrating and directing the flow of heated air issuing from the air outlet of the cover.

3. In a hair drier, an outer cover, a hull within and spaced therefrom, a Venturi structure within and substantially spaced from said hull, an electric heating element within the lower end of the Venturi, the bottom of the cover having air inlet perforations, the hull and the Venturi structure having bottom air inlets and top air outlets, said cover having a single air outlet at the top of its front wall, the upper wall portions of the Venturi structure, the hull and the cover being inclined and directed toward the air outlet of the cover, as are also the top air outlets of the hull and the Venturi structure, an insulating shield member arranged between the bottom of the Venturi structure and the perforated bottom of the cover, and adjustable means associated with the upper end of the cover for concentrating and directing a hot air current issuing from the air outlet of the cover.

4. In a hair drier, a Venturi structure composed of lower and upper members connected with each other at and forming a joined throat portion, the lower member having a closed bottom and side air intakes arranged near that bottom, an electric heating element disposed within said lower member, the upper member terminating in a single side air outlet; a hull substantially completely enclosing and being spaced from said Venturi structure and having air intakes at the bottom and air outlets at the top end adjacent the air outlet of the Venturi structure; a substantially fully closed cover completely housing and being spaced from said hull, the bottom of the cover having air inlet perforations, an air outlet provided at the top end of the front wall of the cover; the upper wall portions of the Venturi structure, of the hull and of the cover being inclined and being directed toward the air outlet of the cover; an insulating shield interposed between the closed bottom of the Venturi structure and the perforated bottom of the cover; the cover having insulated walls; adjustable and bodily movable means for directing and concentrating hot air issuing from the air outlet of the cover; and an adjustable support for the cover associated with its bottom.
